Inventor:

Wm G. Creamer

UNITED STATES PATENT OFFICE.

WILLIAM G. CREAMER, OF BROOKLYN, NEW YORK.

AUTOMATIC CAR-VENTILATOR.

SPECIFICATION forming part of Letters Patent No. 398,882, dated March 5, 1889.

Application filed March 26, 1887. Serial No. 232,603. (No model.)

To all whom it may concern:

Be it known that I, WILLIAM G. CREAMER, a citizen of the United States, residing at Brooklyn, in the county of Kings and State of New York, have invented new and useful Improvements in Automatic Car-Ventilators, (for which patents were granted to me August 21, 1861, and February 20, 1872,) of which the following is a specification.

10 My invention relates, mainly, to improvements to stop the noise caused by the quick vibration of the automatic deflectors by the rapid action of the wind when the car is stationary. These ventilators are mainly used 15 on railroad passenger-cars, and any noise is very objectionable when the car is at rest, especially on night-cars. The invention of 1872 (bushing the pivots with rubber) diminished the noise very much, but failed to stop it entirely. At that time, also, I used an india-rubber stop at the end of the deflector; but this did not effect the purpose entirely. I now place the first stops close up to the pivot, and the shock of the strike is thereby much 25 diminished. This in connection with the elastic-strip joint now stops the noise entirely; also, improvements by which, when the car is at rest, the deflectors will stand out at right angles with the body of the car, in order that 30 the counter-current of air may the more readily put the deflector in the oblique position required to exhaust the air from the inside of the car; also, that in a hard rain the water will not lead into the car at the inner end of 35 the deflector between the end of it and the body of the ventilator; also, the additional protection of a hooded covering to the deflector which prevents cross-winds from entering the car. I attain these objects by the improvements shown in the accompanying drawings, in which—

Figure 1 represents a section of one side of the clear-story of a railroad-car with the ventilator in its position with the car at rest. Fig. 2 represents the ventilator and hood only as seen on the side of the car. Fig. 3 represents the plan of the ventilator, showing various positions of the automatic deflector at rest and when moving to right or left; also, the hooded covering to prevent the entrance 45 of rain in cross-winds and the body of the

ventilator in the side of the clear-story of the car.

Similar letters refer to similar parts throughout the several views.

In Fig. 1 the automatic deflector A is shown in its natural position when the car is at rest, standing out at right angles from the car. This position it takes because the top pivot, G, is set out about three-quarters of an inch 55 outside the perpendicular line of the one at the bottom H. The hooded covering F F F is also shown, and is open at each end.

Fig. 2 shows the hood-covering F F in outline with the dotted lines behind, showing the 60 ventilator and deflector A in the position taken when the car is moving to the right.

Fig. 3 shows the deflector A in its position when the car is at rest, and as soon as it moves to the right the resistance of the air puts it 65 in the position shown by the dotted lines C.

Without the arrangement of the pivots G H the deflectors would be liable to stand in the oblique position shown at B, and then the air would drive into the car until it had attained 70 considerable speed. When the car moves to the left, the deflector A takes the position shown by the dotted lines B. Close to the pivot on each side I place small blocks of rubber, E E, which the deflector A strikes noiselessly as it 75 takes each of its positions. At the same time the inner end of the deflector A at I presses up against a thin rubber strip, D D, forming a tight joint by the pressure of the air on the outer end of the deflector A, keeping it tight 80 up against the elastic strips D D. The body of the ventilator, the deflector, and hood are made of tin.

A brief summary of its action is as follows: When the car is stationary, all the several deflectors, of which there are usually eight on each side of the clear-story, stand out at right angles, as shown in Fig. 1. When the train starts, the opposing air strikes squarely 90 against the deflector, and it then moves backward and strikes the little rubber cushion E, and as the speed and pressure increase the inner end of the deflector presses up against the vertical rubber spring D and forms a tight joint. The current of air contracted to a jet 95 by the hood acts much like a jet of water in a still pond, causing a strong suction of air

from the inside of the car outward, all the ventilators acting simultaneously.

I claim—

1. In a car-ventilator, a deflector pivoted in the air-exit opening and having the upper pivot nearer than the lower to the outer edge of the deflector, whereby the deflector tends normally to assume a position at right angles to the side of the car.
2. The combination, with the pivoted de-

flector, of elastic strips located on each side of the pivot, and as close as possible thereto, and elastic strips located as described, so as to form a tight joint with the inner edge of the deflector in either position.

WM. G. CREAMER.
